W. H. WELLS AND JOSEPH HAWSE, OF NEWPORT CENTRE, VERMONT.

Letters Patent No. 69,288, dated September 24, 1867.

IMPROVED CLOTHES-PIN.

The Schedule referred to in these Letters Patent and making part of the same.

TO ALL WHOM IT MAY CONCERN:

Be it known that we, W. H. WELLS and JOSEPH HAWSE, of Newport Centre, in the county of Orleans, and State of Vermont, have invented a new and improved Clothes-Pin; and we do hereby declare that the following is a full, clear, and exact description thereof, which will enable those skilled in the art to make and use the same, reference being had to the accompanying drawings, forming part of this specification.

The present invention relates to a pin or clamp for confining a line and clothes and other materials hung or suspended thereon, which pin or clamp is formed of a continuous wire that, between its two ends, is coiled sufficiently to give it a spring or elasticity, and at each end is provided with an arm or roller, attached thereto in any suitable manner. In the accompanying plate of drawings our improved clothes-pin or clamp is illustrated—

Figure 1 being a side or face view of the same, and

Figure 2 an edge view.

Similar letters of reference indicate corresponding parts.

A, in the drawings, represents our improved clothes-pin or clamp. This clothes-pin is made from a wire, *a*, that, between its two ends *b*, is coiled to a degree sufficient to give its arms *B* elasticity or spring enough to close, by the rollers or arm *C* applied to such end, against each other, and there be held, consequently confining the line and the clothes, &c., suspended thereon, between the two arms, as shown in red at *D*.

We claim as new, and desire to secure by Letters Patent—

The clothes-pin, constructed as described, having its ends *b* bent at right angles to the body, to receive the rollers *C*, which press against each other beneath the clothes-line, the latter being placed at *D*, between the arms *a a*, as herein shown and described.

W. H. WELLS,
JOSEPH HAWSE.
